UNITED STATES PATENT OFFICE.

JULIUS FEKETE, OF NEW YORK, N. Y.

ATTACHMENT FOR BOWLING ALLEYS.

Application filed June 2, 1924. Serial No. 717,265.

To all whom it may concern:

Be it known that I, JULIUS FEKETE, a citizen of the United States, and resident of the city of New York, in the county of Bronx and State of New York, have invented certain new and useful Improvements in Attachments for Bowling Alleys, of which the following is a specification.

The present invention relates to improvements in attachments for bowling alleys, and has for its main object to provide a simple and inexpensive device for attachment to the return trough of a bowling alley for removing dust and dirt which may 15 adhere to the balls, at the same time retarding the balls as they are returned to the players' stand.

Another object of the invention is to provide a device of the character mentioned 20 which is simple in construction, efficient in operation and capable of manufacture on a commercial scale, or in other words one which is not so difficult to make as to be beyond the reasonable cost of such a contrivance.

With these and other objects in view, which will more fully appear as the nature 25 of the invention is better understood, the same consists in the combination, arrangement and construction of parts hereinafter described, pointed out in the appended claims and illustrated in the accompanying drawings, it being understood that many changes may be made in the size and proportion of the several parts and details of 30 construction within the scope of the appended claims, without departing from the spirit of sacrificing any of the advantages of the invention.

One of the many possible embodiments 35 of the invention is illustrated in the accompanying drawings, in which:—

Figure 1 is a side elevation of a portion 40 of the return track of a bowling alley with the invention applied thereto; Fig. 2 is a section taken on line 2—2 of Fig. 1, on a larger scale; Fig. 3 is a side elevation of the attachment, also on a larger scale; and Fig. 4 is a section taken on line 4—4 of 45 Fig. 2, on a still larger scale.

In the drawings, the numeral 10 indicates the return trough of a bowling alley, on which both ten-pin and duck-pin balls are adapted to roll. This trough comprises 50 a pair of spaced parallel rails 11, to the

outer vertical faces of which is attached, adjacent the players' stand, a ball cleaning and retarding device 12. The ball cleaning and retarding device is in the form of a tunnel for the balls, it comprising an 60 outer hood 13 of substantial length, the same being for the most part cylindrical in shape and, preferably, made of cardboard. This hood is lined with a cleaning surface 14, that may consist of a fur 65 piece, having its fur fibres 15 directed inwardly, or it may be in the form of a sheet, carrying inwardly directed tufts or bristles, as the case may be. The cleaning surface may be attached to the hood in any suitable manner, for instance by rivets 16, or by detachable fastening devices. To the outer face of the hood 13 are secured by some of the fastening devices 16, adjacent both ends of the said hood, open metallic 70 rings 17, one purpose of which is to keep the hood in shape. The edges of the fur are covered all around by binding strips 18, preferably, of cardboard, some of the fastening means 16 passing through these 75 binding strips. The tunnel so formed is secured to the outer vertical faces of the rails 11. There are two securing means mounted upon each vertical rail, each consisting of a metal clip 19, one end of which 80 abuts against the rail and being attached thereto, for instance, by screws 19', passing into the said rail. The clip is then bent outwards as shown at 20, running then in parallel relation to the rail, as indicated at 85 21, it being then bent back upon itself at 22, the backwardly extending portion 23 being spaced from the portion 21 and running parallel thereto. Through the portion 23 extends a hole 24, in alignment with 90 a screw-threaded hole 25 in the portion 21. The pair of clips on each rail are spaced apart a distance which corresponds to the 95 length of the hood 13, they being arranged in opposing positions so that, when the hood and the elements thereon are inserted between the portions 21 and 23 of the said 100 clips, they will not only be held against lateral movement but also against longitudinal shifting.

Each of the open metallic rings 17 is provided adjacent each end with a vertical row of holes 26, which are punched also throughout the cleaning surface and the adjacent binding strips 18. These holes are 110

arranged in such a manner that they may be brought into alignment with the registering holes 24 and 25 in the clips. For holding the tunnel in position upon the clips, 5 screws 27 are provided, having for instance knurled heads 28, so that they may be screwed home without the aid of special tools. These screws extend through the holes 24 in the clips and through the holes 10 26 in the metallic rings, their threads being engaged with the threads of the holes 25 in the clips and then screwed home. The metallic rings 17 are provided adjacent their ends with a row of holes, in order 15 to permit the size of the tunnel to be varied so that the ball and retarding device may be used not only for ten-pin balls but also for duck-pin balls. The tunnel is furthermore made adjustable to exert the proper 20 retarding effect on the balls, and also to compensate for wear of the cleaning element.

From the foregoing it appears that the device is of such nature that it can be readily 25 applied to the ordinary trough of a bowling alley and to any portion thereof, that is to say either to the elevated portion 29 adjacent the buffer post 30 or the inclined portion 31 of the trough. In fact, it may 30 be secured to the lower portion 32, if convenient.

For the purpose of reducing the size of the tunnel, both longitudinal free edges of the hood 13 may be shifted downwards, or 35 only one of the same.

The clips are spaced from the rails 11 of the return trough to provide space for the tufts, fibers or bristles on the cleaning

surface, when the size of the hood is to be adjusted on the trough. 40

What I claim is:—

1. The combination with a bowling alley return trough including two spaced parallel rails, of a set of two clips secured to each rail, a hood extending through said clips, and co-acting means on said hood and said clips for adjustably fastening said hood to said rails. 45

2. The combination with a bowling alley return trough including two spaced parallel rails, of a set of two oppositely disposed clips secured to each rail, a hood extending through said clips, and co-acting means on said hood and said clips for adjustably fastening said hood to said rails. 50

3. The combination with a bowling alley return trough including two spaced parallel rails, of a set of two clips secured to each rail, a hood extending through said clips provided with a vertical row of holes in operative relation to each clip, and a clamping screw on each clip adapted to be engaged with any member of the respective row of holes in said hood. 60

4. In a device according to claim 1, those portions of said clips through which said hood extends being spaced from said rails. 65

5. In a device according to claim 3, those portions of said clips through which said hood extends being spaced from said rails. 70

Signed at New York, in the county of New York, and State of New York, this 20th day of May, A. D. 1924.

JULIUS FEKETE.
